UNITED STATES PATENT OFFICE

107,619

DESIGN FOR A POT HOLDER OR THE LIKE

May Marshall Sieverling, Burdett, Kans.

Application July 20, 1937, Serial No. 70,543

Term of patent 3½ years

To all whom it may concern:

Be it known that I, May Marshall Sieverling, a citizen of the United States, residing at Burdett, in the county of Pawnee and State of Kansas, have invented a new, original, and ornamental Design for a Pot Holder or the like, of which the following is a specification, reference being had to the accompanying drawing, forming part thereof.

I claim:

The ornamental design for a pot holder or the like as shown.

MAY MARSHALL SIEVERLING.
